STROBOSCOPIC CATHODE-RAY OSCILLOSCOPE SYSTEM FOR COMPARING TWO FREQUENCIES

Robert T. Adams, Baltimore, Md., assignor to Western Electric Company, Incorporated, New York, N. Y., a corporation of New York

Application February 8, 1944, Serial No. 521,568

4 Claims. (Cl. 172—245)

1

This invention relates to electrical testing and more particularly to a method of and apparatus for comparing frequencies.

In the prior art frequencies have been compared by causing them to produce stationary, reentrant patterns known as Lissajous figures. Where the frequency ratio is a harmonic ratio which may be represented by small whole numbers, this method is easy to use. However, where the frequencies are nearly equal and in a ratio which must be represented by large whole numbers, the patterns produced often get so complicated as to become worthless. Nevertheless the simplicity of the direct comparison method is very desirable.

It is the object of this invention to provide a method of and a means for directly comparing two nearly equal frequencies even though they differ sufficiently to produce an unintelligible pattern compared by the usual means.

The foregoing object is attained by providing a method of and an apparatus for causing the unknown frequency and the standard frequency to cooperate in producing a Lissajous figure and stroboscopically interrupting the production of said figure at a known frequency.

The invention may be better understood by referring to the accompanying drawings in which:

Fig. 1 is illustrative of an embodiment of the invention;

Fig. 2 is a series of Lissajous figures illustrating the principles of the invention;

Fig. 3 is a Lissajous figure which may result when two frequencies are nearly equal and their ratio is represented by relatively large integers; and,

Fig. 4 shows a simpler pattern derived from the pattern of Fig. 3 in accordance with the teaching of this invention.

In Fig. 1 a standard source of frequency 1 is applied to one pair of the deflector electrodes 6 of a cathode ray oscilloscope 3 while an unknown frequency source 2 is applied to the other pair of electrostatic deflector plates of the same oscilloscope. Oscilloscope 3 includes in addition to the electrostatic deflector plates 6 an electron gun which may comprise an indirectly heated cathode 7, an intensity control electrode 8, and one or more other electrodes represented schematically as 9. While a particular form of oscilloscope tube has been shown schematically in Fig. 1, any of the conventional forms may be employed in the practice of this invention. For example, instead of the electrostatic deflector plates 6, electromagnetic deflector coils may be used or the beam may be deflected along one axis by electrostatic

2

means and along the other axis at right angles thereto by electromagnetic means.

Connected to the cathode 7 and intensity control electrode 8 is a variable low frequency calibrated oscillator 10. The voltage output of this oscillator is so adjusted as to periodically blank or release the beam generated by the electron gun of oscilloscope tube 3.

As is customary in oscilloscope practice, amplifiers may be employed in any of the deflector or control electrode channels. For example, the standard frequency source may be amplified by an amplifier 4, the output of which is coupled to the corresponding deflector plates through a coupling condenser and resistor as indicated in Fig. 1. Similar connections through an amplifier 5 are shown for the unknown frequency source 2.

The production of Lissajous figures by the means of a cathode ray oscilloscope is so well known that it need not be described in detail. It need only be remembered that regardless of the two frequencies combined on the deflector plates of the oscilloscope, the pattern will always be reentrant and where the frequencies approach equality the pattern will repeat itself at a rate equal to the difference between the two frequencies. In so far as the effect on the eye is concerned, this pattern becomes entirely unintelligible when the frequency difference is greater than 10 to 15 cycles per second and the frequency ratio must be represented by large numbers. The Lissajous figures 11 represented in Fig. 2 are for the special cases where the two frequencies are equal but differing in phase as indicated by the angles shown directly below the several figures. It is a well-known fact that where the frequency difference is in the order of 2 or 3 cycles per second, or less, and the frequency ratio contains large integers, the discrete Lissajous figures as shown in Fig. 2 appear to successively form one after another as if a hoop were being rotated about a substantially vertical axis and at the same time the axis was being oscillated to 45 degrees on either side of the vertical line. The vectors 12 in Fig. 2 are shown to illustrate the phase angles between the standard and unknown voltages, the standard voltage being used as a reference vector and designated with a reference character S, while the unknown voltage is represented by the vector U. The curved arrow adjacent the unknown voltage vector U represents counterclockwise rotation with respect to the standard frequency reference vector S. The resulting image on the oscilloscope screen will appear similar to that shown in Fig. 3 whenever the frequency ratio contains large numbers

and the frequency difference exceeds about 10 cycles per second. In the previous simplified description of the production of these Lissajous figures, it must be remembered that figures 11 shown in Fig. 2 are the figures that would be produced should the phase angle remain fixed at the angles indicated. The actual path of the beam is a little more complicated by reason of the fact that the phase angle is uniformly shifting. If the frequencies are large enough, the pattern may become reentrant at a rate more rapid than the persistence of vision and consequently the reentrant Lissajous figure appears stationary to the eye. When the two frequencies are nearly equal, the pattern becomes reentrant once for each complete cycle of frequency difference between the standard and unknown frequency sources. Consequently, if the trace can be blanked out once for each cycle of frequency difference, and for the major portion of that cycle, substantially only one epoch of the complicated Lissajous figure 13 of Fig. 3 will appear on the screen as shown at 14 in Fig. 4. Furthermore, if this blanking frequency differs slightly from the difference frequency between the standard and unknown sources, this figure 14 of Fig. 4 will not remain stationary but will seem to go through the various phases indicated at 11 in Fig. 2. When the blanking frequency is made exactly equal to the difference frequency, this stroboscopic image 14 shown in Fig. 4 will be stationary.

The action just described is preferably produced by the apparatus of this invention by employing a variable low frequency calibrated oscillator 10 as shown in Fig. 1 which produces a peaked output as indicated at 10'. The circuits are preferably so arranged that the beam is blanked out except during the peaked periods of the peaked voltages 10' from the variable low frequency calibrated oscillator 10. By reason of the stroboscopic action produced by this low frequency oscillator, it is evident that the frequency thereof will be equal to the difference frequency between the standard source 1 and the unknown frequency source 2 when the stroboscopic figure is made stationary. Consequently the unknown and standard frequency sources may be applied to the beam deflector electrodes of the oscilloscope 3 and the variable low frequency calibrated oscillator adjusted until the stroboscopic image appears stationary on the screen as shown at 14 in Fig. 4. The frequency as then indicated by the calibrated low frequency oscillator will be equal to the difference frequency between the standard and the unknown sources.

What is claimed is:

1. The method of comparing an unknown frequency with a standard frequency comprising causing said frequencies to cooperate to produce a Lissajous figure, stroboscopically interrupting the production of said figure by employing a variable frequency of known magnitude, and adjusting the magnitude of said variable frequency until said interrupted figure appears stationary, whereupon the magnitude of said variable frequency is a measure of the difference between the standard and unknown frequencies.

2. An apparatus for comparing the frequency of a source of unknown frequency with a source of standard frequency comprising in combination a cathode ray oscilloscope including horizontal and vertical beam deflecting means and a beam intensity control electrode, a calibrated variable frequency source, means connecting said source

of standard frequency to one of the beam deflecting means, means connecting the source of unknown frequency to the other beam deflecting means, means connecting the calibrated variable frequency source to the beam intensity control electrode, and a bias source for said beam intensity control electrode, said source being adjusted to normally suppress the beam until the positive peak voltage from said variable frequency source exceeds a predetermined limit whereupon said beam may be interrupted at a frequency equal to the difference between the standard and unknown frequencies.

3. An apparatus for comparing the frequency of a source of unknown frequency with a source of standard frequency comprising in combination a cathode ray oscilloscope including horizontal and vertical beam deflecting means and a beam intensity control electrode, a calibrated variable frequency source of the type which produces peaked voltage pulses of short duration relative to the period of the cycle, means connecting said source of standard frequency to one of the beam deflecting means, means connecting the source of unknown frequency to the other beam deflecting means and means connecting the calibrated variable frequency source to the beam intensity control electrode, whereby said beam is caused to form a Lissajous figure only during the short duration of said peak voltage from the variable frequency source.

4. An apparatus for comparing the frequency of a source of unknown frequency with a source of standard frequency, comprising in combination a cathode ray oscilloscope including horizontal and vertical beam deflecting means and a beam intensity control electrode, a calibrated variable frequency source of the type which produces peaked voltage pulses of short duration relative to the period of the cycle, means connecting said source of standard frequency to one of the beam deflecting means, means connecting the source of unknown frequency to the other beam deflecting means, means connecting the calibrated variable frequency source to the beam intensity control electrode and a bias source for said beam intensity control electrode, said source being adjusted to normally suppress the beam until the positive peak voltage from said variable frequency source exceeds a predetermined limit, whereby said beam may be caused to produce the Lissajous figure only during said peak voltage periods of short duration.
